CATALYTIC COMBINATION PROCESS

Robert F. Ruthruff, Chicago, Ill.

Application May 13, 1940, Serial No. 334,741

13 Claims. (Cl. 196—49)

This invention relates to a process for the conversion of hydrocarbon mixtures of wide boiling range into hydrocarbons of high utility and value boiling within the usual motor fuel range. More particularly, this invention relates to a process for the conversion of crude oils into hydrocarbons of high utility and value boiling within the usual motor fuel range. Still more particularly, this invention relates to a process for the conversion of hydrocarbon mixtures of wide boiling range into hydrocarbons of high utility and value boiling within the usual motor fuel range wherein said hydrocarbon mixtures of wide boiling range are separated into a plurality of fractions, some or all of which are then subjected separately but in cooperative combination to catalytic conversion conditions suitable for transforming said fractions into hydrocarbons of high utility and value boiling within the usual motor fuel range. Still more particularly, this invention relates to a process for the conversion of crude oils into hydrocarbons of high utility and value boiling within the usual motor fuel range wherein said crude oils are separated into a plurality of fractions, some or all of which are then subjected separately but in cooperative combination to catalytic conversion conditions suitable for transforming said fractions into hydrocarbons of high utility and value boiling within the usual motor fuel range.

A primary object of my invention is to provide an improved unitary combination cracking process for processing hydrocarbon mixtures of wide boiling range, for example, crude oils, whereby a maximum yield of motor fuel of superior antiknock quality is obtained.

A further object of my invention is to provide a combination cracking process wherein hydrocarbon mixtures of wide boiling range, for example, crude oils, are subjected to a distilling operation to separate a plurality of fractions, some or all of which are subjected to separate but cooperative catalytic conversion processes so as to obtain a maximum yield of motor fuel of superior antiknock quality.

Another object of my invention is to provide a combination cracking process wherein hydrocarbon mixtures of wide boiling range, for example, crude oils, are subjected to a distilling operation to separate a plurality of fractions, some or all of which are subjected to separate catalytic conversion processes wherein by-products from some of said separate catalytic conversion processes are introduced into other of said separate catalytic conversion processes

whereby a maximum yield of motor fuel of superior antiknock quality is produced.

Other objects of my invention will become apparent as the description thereof proceeds.

5 Various thermal procedures for transforming hydrocarbon fractions into hydrocarbons of high utility and value are well known in the art.

While thermal conversion processes give a higher yield of gasoline of higher quality from 10 crude oil than can be attained by simple fractionation of the crude, nevertheless these processes are far from perfect. The ultimate gasoline produced is only of moderate octane rating and considerable improvement in this respect is

15 highly desirable. Also, the gasoline yield is not as high as could be desired because of the loss of potential gasoline as gas and tar. Because of these, and other disadvantages too numerous to mention, within the last few years attention has 20 been directed to the replacing of thermal conversion methods by catalytic conversion methods. For example, catalytic methods for the reforming of naphtha show great advantages over thermal conversion processes. Operating

25 pressures are low, ranging from a little above atmospheric to a maximum of some 300 pounds per square inch, more or less. Operating temperatures are usually slightly lower than those employed in thermal reforming. The yield and

30 quality of the catalytically reformed naphtha are much higher than with thermal reformed naphtha. The catalytically reformed naphtha is rich in aromatics and accordingly has an octane rating considerably higher than that shown

35 by any thermally reformed naphtha. Additionally, the gas formed in catalytic reforming consists largely of hydrogen and as a result the yields of catalytically reformed naphtha are much higher than are obtained in thermal reforming processes where the gas consists largely

40 of gaseous hydrocarbons.

Similarly, the catalytic cracking of gas oil shows many advantages over thermal processes. Operating pressures are moderate, ranging from

45 say 50 pounds per square inch downward while the usual operating temperature is in the range 775° to 975° F. The yield and quality of the gasoline obtained by the catalytic cracking of gas oil are much higher than with thermal conversion processes.

50 The gasoline from catalytic cracking of gas oil has a much higher octane number than thermally cracked material and due to the lower gas yield and zero conversion of charge to liquids of higher boiling point, the 55 theoretical ultimate yield of gasoline by catalytic

cracking of gas oil is higher than that obtained in thermal processes.

While catalytic viscosity breaking has been studied to a certain extent, the results obtained to date are not such as to put the process on a firm commercial foundation. The reason for this is twofold. In the first place, catalytic conversion processes as applied to hydrocarbons preferably and almost of necessity are conducted in the vapor phase and reduced crudes are hard to vaporize completely. Secondly, because of the high carbon to hydrogen ratio of reduced crudes any catalysts used foul very rapidly and hence require regeneration at frequent intervals. Accordingly, in processing reduced crudes by catalytic methods, it is usually preferable to first convert the reduced crude into gas oil and tar (by viscosity breaking) or into gas oil and coke (by coking) and then further process the gas oil thus formed in a catalytic process similar to that described in the previous paragraph.

As far as I am aware no one has previously suggested a combination process for the conversion of hydrocarbon mixtures of wide boiling range, crude oil, for example, wherein the usual fractions treated in the now familiar thermal combination processes of the prior art are subjected to separate but cooperative catalytic conversion processes to produce a maximum yield of motor fuel of superior antiknock quality. I have found that by employing catalytic methods in a combination process for the conversion of hydrocarbon mixtures of wide boiling range, crude oils, for example, the various catalytic zones cooperate with one another in a unique and highly beneficial manner and as a consequence, the overall results are markedly superior to those obtained by conducting the various operations separately.

Many variations are possible in the practice of my invention and accordingly it is impossible to encompass all of them in a brief exposition thereof. However, to indicate the spirit, but not the scope, of my invention the following brief description thereof is included:

Crude oil is fractionated to produce light naphtha, heavy naphtha, gas oil and reduced crude. The heavy naphtha is catalytically reformed, the resulting reaction products are separated into gas (mostly hydrogen), catalytically reformed naphtha (largely aromatics) and a small amount of material having a higher boiling range than the charge. Preferably, hydrogen formed in the catalytic reforming reaction is in part added to the fresh heavy naphtha charge prior to entering the catalytic reforming zone. However, this recycling of a portion of the hydrogen is not essential and it is to be understood that the catalytic reforming process furnishes net hydrogen in large volumes. The reduced crude is subjected to a once through viscosity breaking operation under thermal conditions. The resulting products are separated into gas, viscosity breaker gasoline, light viscosity breaker gas oil (which is added to the virgin light gas oil) and heavy viscosity breaker gas oil. The heavy viscosity breaker gas oil is catalytically cracked, the reaction products being separated into gas, gasoline and bottoms. The mixture of virgin light gas oil and light viscosity breaker gas oil is also catalytically cracked and the resulting products are separated into gas, gasoline and bottoms. The bottoms from heavy gas oil catalytic cracking and from light gas oil catalytic cracking are combined and mixed with a por-

tion of the hydrogen produced in the catalytic reforming step and are then catalytically hydrogenated, the resulting products being returned to the crude oil fractionator. The several gasoline fractions are combined to produce the desired ultimate product.

For a more complete understanding of my invention, reference may be had to the accompanying single sheet of drawings forming a part of the instant specification and wherein, the figure is a diagrammatic illustration, partly in section and partly in elevation, of an apparatus suitable for carrying out the process of my invention.

Turning now to the aforementioned figure, hot crude passes through line 1 to the lower portion of fractionating tower 2. The crude, prior to entering fractionating tower 2, is heated by any suitable means (not shown), for example, by being brought into indirect heat exchange relationship with one or more hot streams followed by passage through an ordinary pipe still. Fractionating tower 2 is provided with means for promoting intimate liquid-vapor contact therein, for example, bubble trays 3, although any other suitable means for the purpose may be employed, for example, the tower may be filled with packing material such as Raschig rings. Fractionating tower 2 is also provided with suitable cooling means. This may take the form of one or more closed coils (not shown) disposed in the upper portion of the tower, through which cold fluid, for example, cold crude, is passed. Or, cold liquid of suitable boiling point may be introduced into the tower at one or more points to provide cooling therein as will hereinafter be more fully explained. Obviously, either or both cooling means may be employed or other suitable procedures may be resorted to for the purpose. Fractionating tower 2 is also provided, if desired, with bottom heating means. This may take the form, for example, of an open or closed coil 4 positioned in the lower portion of the tower through which hot fluid is passed. Specifically, fractionating tower 2 may be provided with an open steam coil 4, steam introduced also aiding in stripping lower boiling components from material collecting in the bottom of the tower. Fractionating tower 2 preferably operates at atmospheric or slightly elevated pressure, for example, in the neighborhood of 25 pounds per square inch gage.

A plurality of streams are withdrawn from fractionating tower 2, for example, light naphtha may be taken overhead through line 5, heavy naphtha may be taken from a trapout tray in the upper portion of the tower through line 6, gas oil may be taken from a lower positioned trapout tray through line 7 while reduced crude bottoms may be removed by means of line 8. In general the light naphtha may be taken to represent those portions of the crude boiling up to about 150° to 300° F. Heavy naphtha may be taken to represent material boiling from the final boiling point of the light naphtha up to about 350° to 500° F. Gas oil represents material boiling from the final boiling point of the heavy naphtha up to 650° to 750° F., while the still higher boiling portions of the crude are eliminated as reduced crude bottoms.

If desired, to provide cooling or additional cooling to the upper portion of fractionating tower 2, the light naphtha vapors may be partially or completely condensed in exchanger 9, passed to separator 10 from which a portion of the liquid is moved by pump 11 through line 12 and valve 13 to fractionating tower 2. Remaining light

naphtha may be removed through valve 14 and line 15 to be disposed of as will hereinafter be described. Any small amount of gas in the crude as well as any vaporous portions of the light naphtha may be removed through valve 16 and line 17 to be disposed of as will hereinafter be described.

Reduced crude leaving fractionator 2 through line 8 is moved by pump 18 to coil 19 in furnace setting 20. Pump 18 raises the pressure of the reduced crude stream to some convenient moderate pressure, for example, 50 to 300 pounds per square inch gage, more or less, while the temperature of this stream is brought up to the neighborhood of 850° to 900° F., more or less, during passage through coil 19 in furnace setting 20. Under the conditions imposed, a considerable portion of the reduced crude is viscosity broken, that is, is converted into gas oil with the simultaneous formation of relatively minor proportions of gasoline and gas.

Instead of being thermally viscosity broken, the reduced crude may be coked by known means, the liquid products from this operation being processed as will be described in connection with the products from viscosity breaking furnace 20. If coked, the reduced crude may, for example, be heated to a temperature in the range 875° to 925° F., more or less, during passage through coil 19 in furnace setting 20. The heated material is then discharged into one or more of a plurality of coke drums (not shown) where the material cokes due to its contained heat. Overhead from the coke drums may be passed to a suitable evaporating tower, for example a tower capable of separating heavy gas oil as bottoms, the overhead passing to fractionator 11. While on stream the coke drums operate at a rather low pressure, for example, 25 to 60 pounds per square inch gage or even less. For continuous operation, a plurality of coke drums is employed, one or more drums being on stream while one or more other drums is being cleaned. Or, if desired, the reduced crude may be catalytically hydrogenated to render the material more amenable to subsequent treating, the resulting liquid products from this operation being processed as will be described in connection with the products from viscosity breaking furnace 20. If hydrogenated, the reduced crude may for example be mixed with a suitable catalyst, for example, tin oxalate or the sulfides or oxides of molybdenum or tungsten and a large excess of hydrogen added, the resulting slurry being heated to a temperature of 850° to 950° F., more or less, in coil 19 in furnace setting 20, the pressure being rather high, for example, 1000 to 3000 pounds per square inch gage, more or less. The charge is sent to a reactor (not shown), vapors therefrom being suitably fractionated while bottoms therefrom are recycled.

Material from viscosity breaking coil 19 passes through valve 21 and enters fractionator 22 which preferably operates at somewhat lower pressure than coil 19, for example, at 25 to 75 pounds per square inch gage. Fractionator 22 is provided with bubble trays 23 or other suitable means to promote liquid-vapor contact. Fractionating tower 22 may be provided with upper disposed cooling means and may be provided with lower disposed heating means (not shown).

Bottoms from tower 22 leave through line 24 through valve 25 to vacuum flasher 26. Vacuum flasher 26 is provided with disc and doughnut trays 27 or other suitable means for promoting

liquid-vapor contact and upper disposed cooling means and lower disposed heating means 28 which may take the form of an open steam coil to aid in vaporizing the lighter components of the liquid bottoms in vacuum flasher 26. Vacuum flasher 26 preferably operates at subatmospheric pressure, for example, 0.1 atmosphere, more or less. Bottoms from vacuum flasher 26 leave through line 29 and are moved by pump 30 to storage. Overhead from vacuum flasher 26 leaves through line 31, is cooled in exchanger 32 and condenser 33 and then passes to separator 34. Liquid from separator 34 leaves through line 35 and is moved by pump 36 to line 37. A portion of the liquid passes through valve 38 to the upper portion of vacuum flasher 26 to provide cooling therein, the remainder is heated in exchanger 32 and passes through line 39 to fractionator 22. Separator 34 is connected by means of a line 40 to vacuum pump 41 which preferably takes the form of a barometric condenser.

It will be evident that the tar removed through line 29 will be very heavy and practically worthless as a source of gasoline. Many other methods may be used to secure the elimination of tar having a very low charging stock value. For example, the lighter and accordingly more valuable tar eliminated through line 24 may, if desired, be coked by a method similar to that previously described, or, if desired, it may be hydrogenated by a method similar to that previously described. Or, if desired, this lighter and accordingly more valuable tar may be propane deasphalted. To accomplish this, the cooled tar is mixed with liquid propane and the resulting mixture is heated to precipitate asphalt, the heavy liquid hydrocarbon-propane mixture being passed to a suitable fractionating tower. Obviously, if desired, vacuum flashed tar from line 29 may be coked, hydrogenated or propane deasphalted. However the gasoline value of this material is so low that such treatment is rarely justified.

Heavy viscosity breaker gas oil is drawn from an intermediate point of fractionating tower 22 through line 42 and is moved by pump 43 to coil 44 in furnace setting 45. The liquid in coil 44 is heated to an elevated temperature. If desired, to aid in the vaporization of this material, a fluid having a lower critical temperature than said heavy viscosity breaker gas oil and substantially unreactive therewith, for example, steam or a gas stream made in the process being described, may be added thereto by means not shown. Also, if desired, the heated material may be passed through a separator (not shown) to remove any unvaporized components prior to processing. An ordinary separator similar to those well known in the art may be employed wherein the substantially completely vaporized charge is passed to a well insulated drum preferably provided with baffles or other suitable deentraining means, vapors being taken overhead while unvaporized material is removed as bottoms. Or, if desired, a centrifugal separator may be used, similar, for example, to that described in United States Patent 2,192,214. In any event, to aid in vaporization, the pressure in coil 44 and in subsequent elements should preferably be as little above atmospheric as is consistent with satisfactory operation. The material leaving coil 44 is passed to a catalytic cracking section.

Catalytic reactors may take several different

forms. Among these may be mentioned the following:

1. Single reactors containing a stationary bed of catalyst.
2. Plural reactors containing a stationary bed of catalyst.
3. Reactors designed for use with moving catalysts.
4. Reactors designed for use with powdered catalysts.

While for any given set of conditions, one of the above types of reactors is usually preferable to the others, these types are more or less interchangeable. Simply for purposes of variety and with no intent to limit the description to the particular type selected for any given application, an example of each type of reactor mentioned will be included in the instant description. For the catalytic cracking of heavy viscosity breaker gas oil, a reactor designed for powdered catalyst operation will be described.

The heated material from coil 44 is passed through valve 46 and is then mixed with powdered catalyst introduced through line 47, valve 48 being closed. This catalyst preferably comprises a silica-alumina complex, either natural or synthetic, and for reasons that will hereinafter become apparent is in a highly heated state. On mixing with the heated material entering through valve 46, said material is immediately brought up to reaction temperature and vaporized. If desired, the powdered catalyst may be slurried into the liquid feed prior to entering coil 44 but generally it is preferable to mix catalyst and feed at the point shown. For the catalytic cracking of this stock, a somewhat inactive (comparatively) catalyst is desirable. This stock is high boiling and as it is desirable to operate in the vapor phase or substantially vapor phase a high temperature is required. If the most active cracking catalysts are employed at the high temperatures required for vaporization, it is difficult to control the reaction so as to avoid considerable secondary decomposition. Accordingly, rather inactive cracking catalysts are preferable in this particular catalytic zone. When such comparatively inactive catalysts are employed, operating temperatures in the neighborhood of 950° F. may safely be used, charging about 1 to 3 pounds of catalyst per pound of oil charged to the unit. Suitable catalysts for the purpose include activated montmorillonitic clays, the commercial materials known as Super Fil-trol and Tonsil being particularly useful. Other suitable catalysts, comprising synthetic silica-alumina complexes have been described in my copending applications, Serial No. 305,473 filed November 21, 1939, Serial No. 313,898 filed January 15, 1940 and Serial No. 317,770 filed February 7, 1940.

It may be mentioned in passing that powdered catalyst operation offers the most convenient method to accurately control reaction temperature and contact time and accordingly is the most suitable method to employ if a highly active catalyst is used in the cracking of heavy gas oils. For the same reason, with an inactive catalyst, a higher temperature may be employed when using the powdered catalyst technique than with any other means for contacting catalyst and charge without running any risk of secondary decomposition.

The catalyst, suspended in the vaporized charge, passes through reactor 49 which preferably takes

the form of an elongated conduit wherein the cracking reaction occurs. The reaction products leave reactor 49 through line 50, following which the gaseous reaction products are separated from the solid, suspended catalyst. This may be accomplished by any suitable known means or any combination thereof, a cyclone separator 51 being shown in the figure. Separated catalyst leaves cyclone separator 51 through line 52 and passes to the regeneration element. Prior to regeneration, the separated catalyst is preferably steamed or otherwise treated to remove any adsorbed or absorbed reaction products therefrom by suitable means not shown. The used catalyst in line 52 is suspended in a stream of air or dilute air introduced through line 53 and the suspension is passed through regenerator 54 which preferably takes the form of an elongated conduit wherein regeneration of the catalyst by combustion of carbonaceous residues on the surface thereof occurs. If desired, regenerator 54 may take the form of a plurality of regenerators in series with an intercooler between each pair in order to better control the heat evolved during regeneration. If desired, reactor 49 and regenerator 54 may each take the form respectively of a plurality of reactors in series and a plurality of regenerators in series, an intercooler being interposed between each pair of regenerators, an interheater being interposed between each pair of reactors. As the catalytic cracking reaction is endothermic while the regeneration reaction is exothermic, partial reaction products may be reheated in the interheaters by indirect heat exchange with partial regeneration products which are simultaneously cooled. Thus the interheaters on the one hand and the intercoolers on the other may both be combined in the form of indirect heat exchangers.

The regenerated catalyst suspension leaves regenerator 54 through line 55 following which the gaseous products are separated from the regenerated suspended catalyst by any suitable known means or any combination thereof, a cyclone separator 56 being shown in the figure. Separated catalyst leaves cyclone separator 56 through line 47 for recycling to the cracking zone. Obviously the catalyst is highly heated and a portion of the heat content may be employed to heat and vaporize the charge as previously described. Prior to recycling, the catalyst may be steamed if desired or otherwise treated to remove any adsorbed air from the surface thereof by means not shown. Separated regeneration gas leaves cyclone separator 56 through line 57 and is in part eliminated from the system through valve 58 and is in part recycled by turbine 59 to line 53, necessary make-up air being added through valve 60. Eliminated combustion gas may, if desired, be employed to supply the endothermic heat of reaction to reactor 49 by indirect heat exchange.

Hydrocarbon reaction products leave cyclone separator 51 through line 61 and pass to fractionator 62. This tower is provided with means to facilitate liquid-vapor contact, for example, bubble trays 63 and is also provided with bottom heating means 64 and upper disposed cooling means. The hydrocarbon reaction products are fractionated in tower 62, products heavier than gasoline leaving through line 65 to be further processed as will hereinafter be described, gasoline and lighter products leaving through line 66. Gasoline and lighter products in line 66 are partially condensed in heat exchanger 67 and pass to separator 68. Liquid products are moved by pump 69 and are in part passed through valve 70

and line 71 to the upper portion of tower 62 to provide open reflux therein, the remainder passing through valve 72 and line 73 to be utilized as will hereinafter be described. Gas from separator 68 leaves through line 74 and line 75 to be utilized as will hereinafter be described.

If desired, the heavy viscosity breaker gas oil catalytic cracking step may be eliminated entirely. This is accomplished by closing valve 46 and opening valve 48, the heated heavy gas oil passing then to tower 22. By this means all heavy viscosity breaker gas oil is ultimately converted into viscosity breaker gasoline, light viscosity breaker gas oil and tar. When this procedure is followed it is advisable to operate coil 44 at some convenient elevated pressure, for example, 400 pounds per square inch gage and at a temperature at the coil outlet of 950° F. or in the neighborhood of this figure. In the event that this scheme is used it may be advisable to discharge the products passing through valve 48 to a tower similar to but separate from tower 22. In this way a cracked tar is eliminated free from or substantially free from virgin fractions and is thus eminently suitable for use in the manufacture of road oils.

As will be apparent to those skilled in the art it is also possible to pass the heavy viscosity breaker gas oil in line 42 directly to line 8 for recycling to the furnace coil 19.

If desired, the reduced crude leaving tower 2 through line 8 may be catalytically viscosity broken. To accomplish this, the reduced crude is heated to a temperature in the range 850° to 925° F., more or less, in coil 19, the pressure being comparatively low, for example, 50 pounds or less per square inch gage. The heated and substantially vaporized charge may or may not then be subjected to a separating step, using any suitable means, for example, a drum separator or a centrifugal separator similar to devices already described. Also, if desired, a fluid of lower critical temperature than the reduced crude charge and substantially unreactive therewith, for example, steam or gas made in the process, may be added to the reduced crude charge to facilitate the vaporization thereof. The heated substantially completely vaporized reduced crude charge is then passed to one or more of a plurality of catalytic reactors (not shown) containing comparatively inactive catalytic material, for example, montmorillonitic argillaceous material, pumice, porous earthenware or the like. Reaction products are passed to a tower (not shown) eliminating heavy viscosity breaker gas oil as bottoms, the overhead from said tower passing to fractionator 77. To insure continuous operation a plurality of catalytic reactors is employed, one or more being on stream while the catalytic material in one or more others is being regenerated by procedures known to those skilled in the art and which will be described in somewhat more detail hereinafter.

Returning now to the illustrated embodiment, overhead products from tower 22 leave through line 76 and pass to fractionating tower 77. Fractionating tower 77 is provided with means to facilitate liquid-vapor contact, for example, bubble trays 78, with bottom heating means 79 and upper disposed cooling means. Gasoline and lighter products leave tower 77 through line 80, are partially condensed in heat exchanger 81 and the products are passed to separator 82. Liquid products are moved from separator 82 by pump 83 and are in part passed through valve 84 and line 85 to the upper part of tower 77 to provide open reflux therein, the remainder passing through line 75

86 and valve 87 to be disposed of as will hereinafter be explained. Gaseous products leave separator 82 through valve 88 and line 89. The disposition of these will be explained subsequently. Part or all of the liquid in line 86 may be sent through valve 199 if desired for reasons that will hereinafter be explained.

Bottoms from tower 77, comprising light viscosity breaker gas oil, are moved by pump 90 into line 91 where they are joined with virgin gas oil of approximately the same boiling range which leaves tower 2 by line 1 and is moved by pump 92 into line 91. The combined streams pass to coil 93 in furnace setting 94 and are therein heated to a temperature of from 750° to 950° F., more or less, preferably 800° to 900° F., the pressure being quite moderate, say 50 pounds per square inch gage or thereabouts. The thus heated and vaporized charge passes to reactor 95 wherein it is contacted with a suitable catalytic agent. A quite active cracking catalyst is preferably used in reactor 95. A catalyst such as is made by impregnating silica gel with aluminum nitrate or other thermally decomposable aluminum salt and then igniting may be employed. Or, if desired, catalysts such as are described in my copending applications, Serial No. 305,472, filed November 21, 1939, now U. S. Patent 2,278,590 and Serial No. 300,390, filed October 21, 1939, may be employed in reactor 95. Of course, catalysts such as are described in connection with reactor 49 may be employed in reactor 95 if desired.

Reactor 95 may take any convenient form. In the figure it is shown as being of similar construction to a tubular boiler or heat exchanger. Catalytic material is introduced into the top of reactor 95 through conduit 96, passes downward through the tubes in reactor 95 and is removed from the reactor via conduit 97. If desired, the tubes in reactor 95 may be heated by surrounding them with hot fluid, for example, hot combustion gas from a source later to be revealed, entering through line 98 and leaving through line 99 or vice-versa. Vaporous reaction products leave reactor 95 through line 100.

The descent of the catalyst through the tubes in reactor 95 may be facilitated by means of shakers or other similar devices (not shown). The rate of catalyst addition to and removal from reactor 95 is so regulated that the catalyst removed is exhausted or nearly so. This material is moved through conduit 97 to regenerator 101. The catalyst is moved in conduit 97, as well as in conduit 96, either mechanically or pneumatically, the term pneumatically being employed in its broadest sense. Regenerator 101 preferably takes the form of a multiple hearth furnace, for example, the furnace known in the art as the Herreschoff furnace. In its descent through the multiple hearths of the furnace the catalyst is contacted with a rising stream of air or preferably inert gas containing air introduced through line 102. Carbonaceous deposits are burned from the catalyst in regenerator 101 and hot combustion gases leave through line 103 and are recirculated by turbine 104. Part of these combustion gases are discharged through valve 105 and part or all of these may be introduced into line 98 to supply heat to the tubes in reactor 95. Necessary makeup air is introduced through valve 106. Regenerated catalyst falls to the bottom of regenerator 101, is picked up by conduit 96 and is returned to reactor 95.

For a fuller description and more detailed illus-

tration of reactor-multiple hearth regenerator system reference may be had to my copending application, Serial No. 277,885, filed June 7, 1939.

Vaporous reaction products from reactor 95 are conducted by line 100 to fractionating tower 107. This tower is provided with bottom heating means 108, means to promote liquid-vapor contact such as bubble trays 109, and with top cooling means. Overhead from tower 107 leaves through line 110, is cooled in exchanger 111 and passes to separator 112. Liquids are removed from separator 112 by pump 113, part are passed through valve 114 and line 115 back to the top of tower 107 to provide cooling therein while the remainder pass through line 117 and valve 116 to be disposed of as will hereinafter be described. Gaseous products are removed from separator 112 by valve 118 and line 119. The treatment of these will be described shortly. Bottoms from tower 107 are removed through line 120 to be further processed as will hereinafter be described.

Heavy naphtha is removed from the upper portion of fractionating tower 2 through line 6 and is moved by pump 121 to heating coil 122 in furnace setting 122A. If desired, part or all of the viscosity breaker gasoline from tower 17 may be added to the naphtha charged to the heating coil 122. This may be accomplished by partially or completely closing valve 87 and partially or completely opening valve 199 in line 200. If it is desired to treat only the heavier portions of the viscosity breaker gasoline, line 76 may pass over to tower 2 rather than to tower 17 as shown. In this way, light viscosity breaker gas oil leaves, mixed with light virgin gas oil, through line 7, heavy viscosity breaker gasoline leaves, mixed with heavy virgin naphtha, through line 6 and light viscosity breaker gasoline and light virgin naphtha leave through line 5. By this mode of procedure, obviously tower 17 with all of its auxiliary equipment is unnecessary. Also, if desired, all virgin gasoline may be passed to coil 122. To accomplish this, line 6 is omitted and all components in the crude of gasoline boiling range pass overhead from tower 2, the liquid portions thereof being transferred via line 15 to coil 122 by a line not shown. In this modification, the total viscosity breaker gasoline may be processed in conjunction with the total virgin gasoline by the scheme already described.

The naphtha charge is heated to a temperature of from 875° to 1050° F. more or less, preferably to a temperature within the range 925° to 1000° F. The naphtha may be under a pressure of from atmospheric or somewhat above up to a pressure of 200 to 300 pounds per square inch or higher. The heated and vaporized naphtha passes through line 123 and valve 124 to catalytic reactor 125. Preferably, before entering the catalytic reactor, the naphtha is mixed with hydrogen at a rate of for example 1 to 5 moles per mole of naphtha, said hydrogen being introduced, for example, through line 126, this hydrogen being obtained from compressor 181.

Reactor 125 may take any desired form, for example, the tubular form shown and described with respect to reactor 95. The catalyst in reactor 125 may comprise chromium oxide gel but preferably comprises alumina, especially the variety of aluminum oxide known commercially as "activated alumina," bearing thereon a relatively minor portion, say 1 to 40%, preferably 5 to 10% of a sixth group metal oxide, particularly chromium oxide or molybdenum oxide. Vaporous reaction products leave reactor 125

through valve 127 and travel by line 128 to fractionator 129.

Fractionating tower 129 is provided with bottom heating means 130, means for promoting liquid-vapor contact, for example, bubble trays 131, and top cooling means. Overhead from tower 129 leaves through line 132, is cooled in exchanger 133 and passes to separator 134. Liquid products are removed from separator 134 by pump 135, part passing through valve 136 and line 137 to the top of tower 129 to provide cooling therein, the remainder passing through line 138 and valve 139 to be further processed as will hereinafter be described. Gaseous products are removed from separator 134 by valve 140 and line 141, the further treatment of these being described immediately hereafter. Bottoms are removed from fractionating tower 129 through line 142 and are utilized as described subsequently.

The gas eliminated through line 141 consists essentially of hydrogen but is diluted with more or less gaseous hydrocarbons. If desired, this gas may be subjected to any suitable separation process to give more nearly pure hydrogen. This may be accomplished, for example, by absorbing the greater part of the gaseous hydrocarbons in a suitable liquid. To accomplish this, the gas stream in line 141 may be moved to the lower portion of absorber 143. Absorber 143 is preferably provided with liquid-vapor contact means, for example, bubble trays 144. The ascending gas stream meets a descending stream of absorber oil introduced through line 145 and concentrated hydrogen leaves through line 146. Rich absorber oil is taken from the bottom of absorber 143 by pump 147, is heated in indirect heat exchanger 148 and passes through line 149 to stripper 150. Stripper 150 is provided with bottom heating means 151 and means for promoting liquid-vapor contact, for example, bubble trays 152. Gas comprising predominantly gaseous hydrocarbons is eliminated through line 153 and valve 154 to be further processed as will be described. Stripped absorber oil is removed from the bottom of stripper 150 by line 155, is moved by pump 156 through indirect heat exchanger 148, cooler 157 and line 145 back to absorber 143.

Returning now to reactor 125: When the catalyst in reactor 125 becomes exhausted, the reactor is removed from stream by closing valves 124 and 127, twin reactor 158 being simultaneously put on stream by opening valves 159 and 160. The catalyst in reactor 125 is then regenerated by burning carbonaceous residues therefrom by introducing air or dilute air through line 161 and valve 162, combustion products being removed from reactor 125 via valve 163 and line 164. When the catalyst in reactor 158 is exhausted that in reactor 125 is restored and the functions of the two reactors are then reversed by closing valves 159, 160, 162 and 163, simultaneously opening valves 124 and 127. Exhausted catalyst in reactor 158 is then regenerated by introducing air or dilute air through line 161 and valve 165, removing combustion products through valve 166 and line 164.

It is a characteristic of catalytic conversion processes that the cycle stocks produced are quite refractory and accordingly are generally not suitable for recycling to the catalytic reactor. Accordingly, bottoms from towers 62, 107 and 129 or any combination thereof are hydrogenated to render them amenable to further processing. If desired, only bottoms from tower 62, or only

bottoms from tower 107 or only bottoms from tower 129, or only bottoms from towers 62 and 107, or only bottoms from towers 62 and 129 or only bottoms from towers 107 and 129 may be so treated. The exact arrangement of the overhead system may be changed if desired depending upon the exact method of treating the bottoms. The overhead system shown in the figure is the most flexible system. If bottoms from towers 62, 107 and 129 are combined and hydrogenated it is obviously possible to combine these three towers into a single tower instead of using the three separate towers shown. Likewise, if only bottoms from tower 62 are hydrogenated, then, if desired, towers 107 and 129 may be combined; this same scheme may be followed, if desired, if only bottoms from towers 107 and 129 are to be hydrogenated. Similarly, if only bottoms from tower 107 are to be hydrogenated, then, if desired, towers 62 and 129 may be combined into a single tower; this same design may be followed, if desired, if only bottoms from towers 62 and 129 are to be hydrogenated. Likewise, if bottoms from only tower 129 are to be hydrogenated, then, if desired, towers 62 and 107 may be combined into a single tower; this scheme may be followed, if desired, if only bottoms from towers 62 and 107 are to be hydrogenated.

While various possible combinations for treatment of bottoms have been described it should be pointed out that in general, one or the other of but two systems of working up bottoms is usually followed. In general, bottoms from towers 62 and 107 are combined and hydrogenated while bottoms from tower 129 may or may not be added to this combined stream as desired. Bottoms from tower 129 are small in quantity and have many uses after little or no further processing.

While various tower combinations and various possible ways of working up bottoms have been described, in the description to follow it shall be assumed that three separate towers, 62, 107 and 129, are available and that bottoms from all are combined and hydrogenated.

Bottoms from tower 62 are removed through line 65 and are moved by pump 167 through valve 168 and line 169 to line 173. Bottoms from tower 107 are removed through line 120 and are moved by pump 174 through valve 175 to line 176. Bottoms from tower 129 are removed through line 142 and are moved by pump 170 through valve 171 and line 172 to line 173. Material in lines 173 and 176 are joined and pass through line 177 and are moved by pump 178 to furnace 179, the mixed charge passing through elongated conduit 180 disposed in furnace 179. Prior to entering the furnace coil, the charge in line 177 is mixed with hydrogen fed by compressor 181 to line 182.

Heated material from furnace coil 180 passes by line 183 to catalytic reactor 184. Reactor 184 is provided with a suitable hydrogenation catalyst such as an oxide or sulfide of molybdenum or tungsten, a mixture of sulfides of molybdenum, zinc and manganese or any other suitable hydrogenation catalyst. Operating conditions are so adjusted in reactor 184 that hydrogenation rather than destructive hydrogenation is the predominant reaction occurring therein. In other words, an attempt is made to convert the various refractory tower bottoms to materials of approximately the same boiling range but more amenable to catalytic conversion processes. No attempt is made to convert these tower bottoms into

gasoline through destructive hydrogenation although normally a small amount of material in the gasoline boiling range is produced. To accomplish this desired end, operating conditions in reactor 184 are relatively mild. The operating pressure is low, for example, in the range 500 to 1500 pounds per square inch and the operating temperature is in the range 850° to 900° F., more or less. About one to ten moles of hydrogen per mole of charge are employed.

Obviously, destructive hydrogenation may be employed if desired. Many factors however militate against its use. In the first place, operating conditions must be quite severe resulting in large equipment and processing costs. Also, large amounts of hydrogen are consumed and this usually necessitates the construction of a hydrogen producing element which is charged, for example, with gaseous hydrocarbons made in the process.

Reaction products from tower 184 pass via line 185 through cooler 186; through reducing valve 187 to separator 188. Hydrogen and other gaseous products are passed by pump 189 and line 190 to absorber 143 for purification as previously described. Liquid products from separator 188 are moved by pump 191 through line 192 to line 1. These enter line 1 preferably prior to the heating means (not shown) used to pre-heat the crude charge in line 1.

As the catalyst employed in reactor 184 has extremely long active life only one reactor is shown. When, after many months, the catalyst becomes inactive the unit may be shut down, the catalyst removed from reactor 184 and replaced by fresh material.

If desired, part or all of the bottoms from tower 62 may be removed to storage or otherwise through line 193 and valve 194; part or all of the bottoms from tower 107 may be similarly removed through line 195 and valve 196 while part or all of the bottoms from tower 129 may be removed via line 197 and valve 198.

In another modification of possible processes for working up tower bottoms, part or all of the bottoms from tower 107 may be moved through line 195, valve 196 and by a line (not shown) to heating coil 44 in furnace 65 where it is heated and further processed with heavy viscosity breaker gas oil from tower 22. As has been mentioned previously, heavy viscosity breaker gas oil is catalytically converted at temperatures higher than is employed in the catalytic conversion of light gas oil. Cycle stock from the catalytic conversion of light gas oil, while too refractory to be converted at a satisfactory rate if recycled to the light gas oil catalytic cracking zone, can be further processed catalytically in a satisfactory manner if sent instead to the heavy viscosity breaker gas oil catalytic conversion zone where higher temperatures prevail.

The various predominantly hydrocarbon gas streams, for example, the gas discharged through valve 16 and line 17, the gas discharged through valve 74 and line 75, the gas discharged through valve 88 and line 89, the gas discharged through valve 118 and line 119 and the gas discharged through valve 153 and line 154 or any suitable combination of these streams may be combined and treated by any known means, for example, absorption to separate any normally liquid hydrocarbons and if desired, higher molecular weight gaseous hydrocarbons such as normal butane. therefrom, the separated materials be-

ing blended with the gasoline produced or otherwise disposed of as desired.

Similarly, the various naphtha and gasoline streams, or any combination thereof may be combined and stabilized by known means to remove part or all of the four carbon atom hydrocarbons therefrom together with lower boiling hydrocarbons. For example, virgin light naphtha discharged through valve 14 and line 15, viscosity breaker gasoline discharged through line 86 and valve 87, catalytically cracked gasoline discharged through valve 116 and line 117, catalytically cracked gasoline discharged through valve 72 and line 73 and catalytically reformed naphtha discharged through line 138 and valve 139 or any combination of these streams, may be combined and stabilized.

To further elucidate my invention a single specific example thereof is given. It is to be understood that this example is illustrative only and in no way is to be considered as limiting the scope of my invention.

Example

A crude oil of 34° A. P. I. gravity and showing a 10% evaporated point of 240° F., 50% evaporated at 585° F. and 90% evaporated at 760° F. during an A. S. T. M. distillation (designation D86-30) was mixed with a hydrogenated cycle stock from a source hereinafter described and the two were fractionated, giving a light naphtha having a 10% point of 125° F., 50% point of 185° F. and a 90% point of 250° F.; a heavy naphtha having a 10% point of 285° F., a 50% point of 325° F. and a 90% point of 390° F.; a gas oil having a 10% point of 450° F., a 50% point of 540° F. and a 90% point of 635° F. and finally bottoms having a 10% point of 660° F. (In a separate experiment in which the crude oil alone was fractionated into cuts having the boiling ranges specified it was found that 25% of 71° A. P. I. light naphtha having a motor octane rating of 71 was produced, 17% of 49° A. P. I. heavy naphtha having a motor octane number of 45, 29% gas oil and 30% reduced crude bottoms were produced, these fractions representing fresh feed to the system the percentages being by volume).

The bottoms were subjected to a thermal once through viscosity breaking operation using a coil outlet temperature of 870° F. and a coil outlet pressure of 150 pounds per square inch. The viscosity broken products were fractionated with the elimination of a 4° A. P. I. viscosity breaker tar, taking overhead 10% viscosity breaker gasoline having an A. P. I. gravity of 59°, a 10% point of 160° F., a 50% point of 270° F., a 90% point of 355° F. and a motor octane number of 65; 19% of light viscosity breaker gas oil having a 10% point of 470° F., a 50% point of 560° F., and a 90% point of 640° F., the remaining product being heavy viscosity breaker gas oil.

The heavy viscosity breaker gas oil was subjected to catalytic cracking conditions using the powdered catalyst technique. Commercial Super Filtral was employed as catalyst. The catalyst to oil weight ratio was 1.9 and the average reaction temperature was 950° F. While these catalytically cracked products were combined with those from the light gas oil catalytic cracking zone and the two were fractionated together, a grab sample from the operation now being described indicated the production of 40% by volume of gasoline of 79 octane number (motor)

and 10 pounds Reid vapor pressure, 55% cycle stock by volume, 11% gas by weight and 3% by weight of coke and loss.

The light viscosity breaker gas oil, in admixture with the previously mentioned gas oil consisting of light virgin gas oil, was subjected to catalytic cracking conditions using the moving catalyst technique. A synthetic catalyst similar to that described in my copending application Serial No. 305,472, filed November 21, 1939, was employed. This composite feed was heated to 800° F. and charged to the catalyst chamber at a rate of about one volume liquid composite feed per hour per volume of catalyst space. Catalyst was added to and abstracted from the reactor at a rate half as great as the rate of oil feed, i. e., the catalyst holding time was two hours. While the catalytically cracked products were combined with those from the heavy gas oil catalytic cracking zone and the two were fractionated together, a grab sample from the operation now being described indicated the production of 30% by volume of 78 octane number (motor) 10 pound Reid vapor pressure gasoline, 7% by weight of gas, 64% by volume of cycle stock and 1.5% by weight of coke and loss.

The heavy naphtha was catalytically reformed in the presence of a catalyst consisting of 10% chromium oxide on alumina. The liquid charge was mixed with hydrogen at a rate of three moles hydrogen per mole of naphtha charge, the whole was passed at a pressure of 300 pounds per square inch and a rate of one volume of liquid feed per hour per volume of catalyst space through the catalytic reactor, the average temperature being 1000° F. An 80% yield of 80 octane number (motor) liquid boiling within the usual motor fuel boiling range was obtained. The net hydrogen production amounted to slightly more than 500 cubic feet per barrel of naphtha charged. The total gas was subjected to absorption so as to produce a hydrogen rich fraction, a portion of which was recycled as already described, the remainder being employed as will be evident immediately hereafter.

The products formed in the light gas oil catalytic cracking zone and the heavy gas oil catalytic cracking zone were combined and fractionated eliminating gas, gasoline and bottoms. Net hydrogen made in the catalytic reforming zone was added to the bottoms at a rate of five moles per mole and the resulting mixture was passed over tungsten sulfide and oxide on pumice at a temperature of 900° F. and a pressure of 1000 pounds per square inch. The flow rate was so regulated that but little material in the gasoline boiling range was formed. Hydrogen absorption was appreciable however. The reaction products were cooled and separated, gases passing to the previously mentioned absorber while the liquids were mixed with the crude and fractionated to give light naphtha, heavy naphtha, gas oil and bottoms of the boiling ranges already given.

On blending the light naphtha formed in the primary fractionation, catalytically reformed heavy naphtha, viscosity breaker gasoline and the gasoline produced in the two catalytic cracking zones the major ultimate product of the process was obtained.

70 I claim:

1. In the conversion of a hydrocarbon mixture of wide boiling range into hydrocarbons boiling within the usual motor fuel range, the process comprising fractionating said hydrocarbon mixture in a first fractionation zone to form a plu-

rality of condensates including a condensate at least the major portion of which boils within the usual motor fuel range and a condensate at least the major portion of which boils above the usual motor fuel range; subjecting said higher boiling condensate, in the presence of a cracking catalyst, to a conversion temperature under catalytic cracking conditions to effect the formation of a high yield of gasoline components, subjecting catalytically cracked products to fractionation in a second fractionating zone to form a residue and a condensate comprising gasoline; blending the lower boiling condensate from said first fractionating zone with hydrogen from a source herein-after described, subjecting the blend, in the presence of a reforming catalyst, to a conversion temperature under catalytic reforming conditions to effect the formation of a high yield of aromatics within the usual motor fuel boiling range and hydrogen, subjecting catalytically reformed products to fractionation in a third fractionating zone to form a condensate comprising aromatics within the usual motor fuel boiling range and hydrogen; recycling a portion of said hydrogen to the catalytic reforming zone; subjecting the residue from said second fractionating zone in the presence of a hydrogenating catalyst and a portion of said hydrogen to a conversion temperature under hydrogenating conditions to effect the upgrading of said residue and passing upgraded residue to the first fractionating zone.

2. In the conversion of a hydrocarbon mixture of wide boiling range into hydrocarbons boiling within the usual motor fuel range, the process comprising fractionating said hydrocarbon mixture in a first fractionating zone to form a residue and a plurality of condensates including a condensate at least the major portion of which boils above the usual motor fuel range and a condensate at least the major portion of which boils within the usual motor fuel range; subjecting said residue to a decomposition temperature to effect the formation of a high yield of light gas oil components and as low yield of gasoline components, fractionating the resulting products in a second fractionating zone to form a residue and a plurality of condensates comprising light gas oil and gasoline; blending the higher boiling condensate from the first fractionating zone and the light gas oil, subjecting the blend, in the presence of a cracking catalyst, to a conversion temperature under catalytic cracking conditions to effect the formation of a high yield of gasoline components; fractionating catalytically cracked products in a third fractionating zone to form a residue and a condensate comprising gasoline; blending the lower boiling condensate from the first fractionating zone and hydrogen from a source herein-after described, subjecting the blend, in the presence of a reforming catalyst, to a conversion temperature under catalytic reforming conditions to effect the formation of a high yield of aromatics within the usual motor fuel boiling range and hydrogen, fractionating catalytically reformed products in a fourth fractionating zone to form a condensate comprising aromatics within the usual motor fuel boiling range and a gas comprising hydrogen; recycling a portion of said hydrogen to the catalytic reforming zone; subjecting the residue from the third fractionating zone in the presence of a hydrogenation catalyst and a portion of the aforementioned gas comprising hydrogen, to a conversion temperature under hydrogenating conditions to effect the upgrading of said residue and passing upgraded residue to the first fractionating zone.

3. The process in accordance with claim 2, further characterized by the fact that said gasoline from the second fractionating zone is catalytically reformed in admixture with the lower boiling condensate from the first fractionating zone.

4. In the conversion of a hydrocarbon mixture of wide boiling range into hydrocarbons boiling within the usual motor fuel range, the process comprising fractionating said hydrocarbon mixture in a first fractionating zone to form a residue and a plurality of condensates including a condensate at least the major portion of which boils above the usual motor fuel range and a condensate at least the major portion of which boils within the usual motor fuel range; subjecting said residue to a decomposition temperature to effect the formation of a high yield of gas oil components and a low yield of gasoline components, fractionating the resulting products in a second fractionating zone to form a residue and a plurality of condensates comprising heavy gas oil, light gas oil and gasoline; subjecting heavy gas oil in a first catalytic cracking zone and in the presence of a cracking catalyst, to a conversion temperature under catalytic cracking conditions to effect the formation of a high yield of gasoline components, blending the higher boiling condensate from the first fractionating zone and the light gas oil, subjecting the resulting blend in a second catalytic cracking zone and in the presence of a cracking catalyst, to a conversion temperature under catalytic cracking conditions to effect the formation of a high yield of gasoline components; fractionating catalytically cracked products from both catalytic cracking zones in a third fractionating zone to form a residue and a condensate comprising gasoline; blending the lower boiling condensate from the first fractionating zone and hydrogen from a source herein-after described, subjecting the resulting blend, in the presence of a reforming catalyst to a conversion temperature under catalytic reforming conditions to effect the formation of a high yield of aromatics within the usual motor fuel boiling range and hydrogen, fractionating catalytically reformed products in a fourth fractionating zone to form a condensate comprising aromatics within the usual motor fuel boiling range and a gas comprising hydrogen; recycling a portion of said hydrogen to the catalytic reforming zone, subjecting the residue from the third fractionating zone in the presence of a hydrogenating catalyst and a portion of the aforementioned gas comprising hydrogen, to a conversion temperature under hydrogenating conditions to effect the upgrading of said residue and passing upgraded residue to the first fractionating zone.

5. The process in accordance with claim 4, further characterized by the fact that gasoline from the second fractionating zone is catalytically reformed in admixture with the lower boiling condensate from the first fractionating zone.

6. In the conversion of a hydrocarbon mixture of wide boiling range into hydrocarbons boiling within the usual motor fuel range, the process comprising fractionating said hydrocarbon mixture in a first fractionating zone to form a residue and a plurality of condensates including a condensate at least the major portion of which boils within the usual motor fuel range and a condensate at least the major portion of which boils above the usual motor fuel range; subjecting said residue to a decomposition temperature

to effect the formation of a high yield of gas oil components and a low yield of gasoline components, fractionating the resulting products in a second fractionating zone to form a residue and a plurality of condensates comprising heavy gas oil, light gas oil and gasoline; subjecting heavy gas oil in a first catalytic cracking zone and in the presence of a cracking catalyst, to a conversion temperature under catalytic cracking conditions to effect the formation of a high yield of gasoline components, fractionating catalytically cracked products in a third fractionating zone to form a residue and a condensate comprising gasoline; blending the higher boiling condensate from the first fractionating zone and the light gas oil, subjecting the resulting blend in a second catalytic cracking zone and in the presence of a cracking catalyst, to a conversion temperature under catalytic cracking conditions to effect the formation of a high yield of gasoline components, fractionating catalytically cracked products from the second catalytic cracking zone in a fourth fractionating zone to form a residue and a condensate comprising gasoline; blending the lower boiling condensate from the first fractionating zone and hydrogen from a source hereinafter described, subjecting the blend in the presence of a reforming catalyst, to a conversion temperature under catalytic reforming conditions to effect the formation of a high yield of aromatics within the usual motor fuel boiling range and hydrogen, fractionating catalytically reformed products in a fifth fractionating zone to form a condensate comprising aromatics within the usual motor fuel boiling range and a gas comprising hydrogen; recycling a portion of said hydrogen to the catalytic reforming zone; blending the residues from said third and fourth fractionating zones, subjecting the resulting blend in the presence of a hydrogenation catalyst and a portion of the aforementioned gas comprising hydrogen to a conversion temperature under hydrogenating conditions to effect the upgrading of said blend, and passing the upgraded blend to the first fractionating zone.

7. The process in accordance with claim 6 further characterized by the fact that said gasoline from the said fractionating zone is catalytically reformed in admixture with the lower boiling condensate from the first fractionating zone.

8. In the conversion of a hydrocarbon mixture of wide boiling range into hydrocarbons boiling within the usual motor fuel range, the process comprising fractionating said hydrocarbon mixture in a first fractionating zone to form a residue and a plurality of condensates comprising gas oil, heavy naphtha and light naphtha; subjecting said residue to a decomposition temperature to effect formation of a high yield of light gas oil components and a low yield of gasoline components, fractionating the resulting products in a second fractionating zone to form a residue and a plurality of condensates comprising light gas oil and gasoline; blending the gas oil and the light gas oil, subjecting the blend, in the presence of a cracking catalyst, to a conversion temperature under catalytic cracking conditions to effect the formation of a high yield of gasoline components, fractionating catalytically cracked products in a third fractionating zone to form a residue and a condensate comprising gasoline; blending the heavy naphtha and hydrogen from a source hereinafter described subjecting the blend, in the presence of a reforming catalyst, to a conversion temperature under catalytic reforming

conditions to effect the formation of a high yield of aromatics within the usual motor fuel boiling range and hydrogen, fractionating catalytically reformed products in a fourth fractionating zone to form a condensate comprising aromatics boiling within the usual motor fuel range and a gas comprising hydrogen; recycling a portion of said hydrogen to the catalytic reforming zone; subjecting the residue from the third fractionating zone, in the presence of a hydrogenation catalyst and a portion of the aforementioned gas comprising hydrogen, to a conversion temperature under hydrogenating conditions to effect the upgrading of said residue and passing said upgraded residue to the first fractionating zone.

9. The process in accordance with claim 8, further characterized by the fact that said gasoline from the second fractionating zone is catalytically reformed in admixture with the heavy naphtha from the first fractionating zone.

10. In the conversion of a hydrocarbon mixture of wide boiling range into hydrocarbons boiling within the usual motor fuel range the process comprising fractionating said hydrocarbon mixture in a first fractionating zone to form a residue and a plurality of condensates comprising gas oil, heavy naphtha and light naphtha; subjecting said residue to a decomposition temperature to effect formation of a high yield of gas oil components and a low yield of gasoline components, fractionating the resulting products in a second fractionating zone to form a residue and a plurality of condensates comprising heavy gas oil, light gas oil and gasoline; subjecting heavy gas oil in a first catalytic cracking zone and in the presence of a cracking catalyst, to a conversion temperature under catalytic cracking conditions to effect the formation of a high yield of gasoline components; blending the gas oil and the light gas oil, subjecting the resulting blend in a second catalytic cracking zone and in the presence of a cracking catalyst, to a conversion temperature under catalytic cracking conditions to effect the formation of a high yield of gasoline components, fractionating catalytically cracked products from both catalytic cracking zones in a third fractionating zone to form a residue and a condensate comprising gasoline; blending the heavy naphtha and hydrogen from a source hereinafter described, subjecting the blend in the presence of a reforming catalyst, to a conversion temperature under catalytic reforming conditions to effect the formation of a high yield of aromatics within the usual motor fuel boiling range and hydrogen, fractionating catalytically reformed products in a fourth fractionating zone to form a condensate comprising aromatics boiling within the usual motor fuel range and a gas comprising hydrogen; recycling a portion of said hydrogen to the catalytic reforming zone; subjecting the residue from said third fractionating zone in the presence of a hydrogenation catalyst and a portion of the aforementioned gas comprising hydrogen, to a conversion temperature under hydrogenating conditions to effect the upgrading of said residue, and passing upgraded residue to the first fractionating zone.

11. The process in accordance with claim 10, further characterized by the fact that said gasoline from the second fractionating zone is catalytically reformed in admixture with the heavy naphtha from the first fractionation zone.

12. In the conversion of a hydrocarbon mixture of wide boiling range into hydrocarbons boiling within the usual motor fuel range, the process

comprising fractionating said hydrocarbon mixture in a first fractionating zone to form a residue and a plurality of condensates comprising gas oil, heavy naphtha and light naphtha; subjecting said residue to a decomposition temperature to effect formation of a high yield of gas oil components and a small yield of gasoline components, fractionating the resulting products in a second fractionating zone to form a residue and a plurality of condensates comprising heavy gas oil, light gas oil and gasoline; subjecting heavy gas oil in a first catalytic cracking zone and in the presence of a cracking catalyst, to a conversion temperature under catalytic cracking conditions to effect the formation of a high yield of gasoline components, fractionating the catalytically cracked products in a third fractionating zone to form a residue and a condensate comprising gasoline; blending the gas oil and the light gas oil, subjecting the resulting blend in a second catalytic cracking zone and in the presence of a cracking catalyst, to a conversion temperature under catalytic cracking conditions to effect the formation of a high yield of gasoline components, fractionating catalytically cracked products from the second catalytic cracking zone in a fourth fractionating zone to form a residue and a con-

densate comprising gasoline; blending the heavy naphtha and hydrogen from a source hereinafter described, subjecting the blend in the presence of a reforming catalyst, to a conversion temperature under catalytic reforming conditions to effect the formation of a high yield of aromatics within the usual motor fuel boiling range and hydrogen, fractionating catalytically reformed products in a fifth fractionation zone to form a condensate comprising aromatics within the usual motor fuel boiling range and a gas comprising hydrogen; recycling a portion of said hydrogen to the catalytic reforming zone; blending the residues from said third and fourth fractionating zones, subjecting the blend in the presence of a hydrogenation catalyst and a portion of the aforementioned gas comprising hydrogen to a conversion temperature under hydrogenating conditions to effect the upgrading of said residues and passing the upgraded residues to the first fractionating zone.

13. The process in accordance with claim 12, further characterized by the fact that said gasoline from the second fractionation zone is catalytically reformed in admixture with the heavy naphtha from the first fractionating zone.

ROBERT F. RUTHRUFF.
